UNITED STATES PATENT OFFICE.

JOHN O. McKEAN, OF WESTFIELD, MASSACHUSETTS, ASSIGNOR TO
FOSTER MACHINE COMPANY, OF WESTFIELD, MASSACHUSETTS,
A CORPORATION OF MAINE.

TENSION DEVICE FOR WINDING-MACHINES.

No. 838,046.

Specification of Letters Patent.

Patented Dec. 11, 1906.

Application filed October 13, 1905. Serial No. 282,542.

To all whom it may concern:

Be it known that I, JOHN O. McKEAN, a citizen of the United States, and a resident of Westfield, in the county of Hampden and 5 State of Massachusetts, have invented new and useful Improvements in Tension Devices for Winding-Machines, of which the following is a specification.

My invention relates to thread-tension devices, and is particularly adaptable to compensating thread-tensions for winding-machines wherein the ball or cop by reason of the increase of its diameter as the process of winding progresses produces an increased 15 speed of the thread passing to the ball or cop.

As is well known, it is desirable that the drag of the tension device through which the thread is delivered to the traveling guide which lays the ball or cop should be reduced 20 as the winding proceeds and the cop grows so as to offset the tendency to increase the tension on the thread due to the increase in surface speed of the growing cop.

The practice of my invention involves the 25 employment of the speed of the thread as the effective factor for bringing about that adjustment of drag on the thread which is to compensate for the increased thread-speed.

In the drawings heretô annexed I have 30 shown a mechanism which contains my invention.

Figure 1 is a side view of one embodiment of my invention, and Fig. 2 is an end view thereof.

In said drawings, A represents a part of a winding-machine frame upon which are mounted relatively adjustable tension members. While any form of tension members may be used, such as the relatively movable 40 pin-carrying arms shown in Fig. 1 of my Patent No. 753,724, I prefer that form shown in the accompanying drawings, wherein a pair of tension-pins 10 and 11 is fixed to each of a series of disks B, pivoted to a suitable bracket 45 A' upon frame A. Each disk B is provided with a crank-arm C, as shown, secured to the disk-shaft D to rotate the disk and its pins. Each of the crank-arms C C is pivotally connected with the link E, so that all the disks 50 are caused to rotate together. One of the

disks—preferably the upper one of the series—is provided with a lever-arm B', by which that disk is actuated and imparts like movement to all the other disks through the crank-shaft E and the several crank-arms CC. 55

The thread is shown at T, passing in a zig-zag course over the pins and from thence over the friction-operated adjuster, presently to be described, to the usual thread-guide of the machine. (Not shown.) The adjuster is, 60 in effect, an auxiliary motor, itself actuated by the passing thread and in its turn actuating the lever B' and its connecting parts and comprises as its movable and sensitive member the friction-wheel 3, which is rotatively 65 mounted upon a suitable portion of the frame A, so as to be susceptible to turn in response to the frictional drag of the thread T over the grooved rim of said wheel 3. Obviously as the speed of the thread T increases the friction 70 exerted upon the friction-wheel 3 also will increase, and I provide connections between the said frictionally-operated thread-adjuster to the tension device, so that as the speed of the thread increases the corresponding 75 increase in friction upon the adjuster will transmit its effect to the tension members so as to reduce their frictional drag upon the thread, and consequently to compensate for the increased speed of the thread by a reduction of the friction factor at the tension device. In order to accomplish this, I provide 80 a windlass-stud 4, which is integral with or firmly secured to the friction-wheel 3 and is preferably axially coincident therewith. 85

The connection between the windlass-stud and the tension device consists of a cord or strap 5, secured at one end to the side of the windlass-stud 4 and at the other end to the arm or lever B', through which all the disks B and their tension-pins are actuated. The diameter of the windlass-stud 4 is small as compared with the friction-wheel 3, and consequently the frictional effect or drag of the thread T upon the wheel 3 exerts a multiplied power effect upon the cord 5, secured to the lever-arm B', and thus upon the tension-disks B. The link E carries weights 8, which may be increased or diminished at will in order to vary the tension effect of the tension- 95 100

pins 10 11. These weights 8 act in opposition to the pull of the cord 5.

As shown in the drawings, the tension has been reduced by the raising of weight 8 by 5 the adjuster or auxiliary motor 3 4 from its lowest position in which the arms C would by weight 8 be drawn downward into a vertical position, and it will be obvious that the weight becomes constantly more effective 10 by increased leverage as the arms C are swung from the vertical position to a position perpendicular to the vertical position. As shown, the arms C have been moved about half this distance.

15 While the compensating tension device as heretofore described is effective to adjust the tension constant of the thread T to the increased speed due to the enlargement of the cop, I have found it advisable to provide the 20 apparatus with a counterbalance which modifies the resultant effect of thread and friction thereof upon the friction-wheel. This counterbalance 2 is shown as mounted upon a crank-arm 13, which in turn is secured to the friction-wheel 3, so as to turn therewith. The crank-arm 13 and counterbalance 2 are so adjusted with relation to the other parts of the device that as the wheel 3 turns in response to the friction of the thread T the 25 counterbalance 2 rises and approaches the gravitational dead-point immediately above the axis of the wheel 3. When the thread-speed becomes very high, the crank 13 is carried past the gravitational dead-point, the 30 weight 2 adds its effect to the friction of the thread T upon the wheel 3, and this effect increases proportionately as the counterbalance 2 recedes from the gravitational dead-point.

40 As the wheel 3 turns in response to friction of the thread T the cord 5 is wound upon the windlass-stud 4 and draws the lever-arm B' upward, thus causing the pins 10 and 11 to diminish the angular course of the thread 45 about the pins, and thus to reduce the friction factor due to the operation of the tension pins. The cord 5 is connected with the stud 4 at an angle, as shown in Fig. 2, so that it will wind upon the stud spirally and not 50 overlie itself as it would if it were connected perpendicularly with the stud.

Other specific forms of adjustable tension members and associated tension-adjuster may be employed without departure from 55 the substance of my invention.

I claim—

1. The combination in a compensating tension device, of an adjustable tension member and an adjuster movable in response 60 to thread friction, both engaging a moving thread frictionally, and connection between the adjuster and the tension member, to move the latter to position of diminished

thread friction as the speed of the thread and consequent friction on the former is increased.

2. In a compensating tension device, the combination of an adjustable tension member, and a friction-wheel rotatable in response to thread friction, both to engage a moving thread frictionally, and connections between the friction-wheel and tension member, to move the latter to a position of diminished thread friction as the former is moved by increased thread speed and friction 75 consequent thereupon.

3. In a compensating tension device, the combination of a pin-carrying tension member adjustable to vary the angularity of thread turns about the pins, said pins, and a friction-wheel to engage the thread passing from the tension member, a windlass-stud operated by the friction-wheel and a cord connection between said stud and the tension member.

4. In a compensating tension device, the combination of a pin-carrying tension member relatively adjustable to vary the angularity of thread turns about the pins, said pins, a friction-wheel to engage the thread 90 passing from the tension member, a counterbalance carried by the friction-wheel, a windlass-stud operated by the friction-wheel, and a cord connection between said stud and tension member.

5. In a compensating tension device, the combination of an adjustable tension member, an adjuster comprising an auxiliary motor actuated by the passing thread, the tension member and auxiliary motor engaging the moving thread frictionally, and connections between the motor and the tension member to move the latter in a position of diminished thread friction as the speed of the thread and consequent frictional effect upon the motor is increased, and a counterweight actuated by the friction-wheel to supplement the effect of a moving thread thereon.

6. In a compensating tension device, the combination of an adjustable tension member, an adjuster comprising a tension-wheel movable in response to said friction, the tension member and friction-wheel to engage a moving thread frictionally, and connections between the friction-wheel and tension member to move the latter to a position of diminished thread friction as the speed of the thread and consequent frictional effect upon the wheel is increased, and a counterweight actuated by the friction-wheel to supplement the effect of a moving thread thereon.

7. In a compensating tension device, the combination of pin-carrying tension members, relatively adjustable to vary the angularity of the thread about the pins; a friction-wheel to engage the thread passing from the

5 tension members, a counterbalance actuated by the friction-wheel and movable thereby in one direction toward and from a gravitational dead-point, and connections between the friction-wheel and the pin-carrying tension members to adjust the latter by movement of the friction-wheel.

Signed by me at Westfield, Massachusetts, this 5th day of October, 1905.

JOHN O. McKEAN.
